US0D1012231S

(12) **United States Design Patent** (10) **Patent No.:** **US D1,012,231 S**
(45) **Date of Patent:** **** Jan. 23, 2024**

(54) **SHOWER HEAD**

(71) Applicant: **HANSGROHE SE**, Schiltach (DE)

(72) Inventor: **Matthias Oesterle**, Winterbach (DE)

(73) Assignee: **Hansgrohe SE**, Schiltach (DE)

(**) Term: **15 Years**

(21) Appl. No.: **29/831,066**

(22) Filed: **Mar. 17, 2022**

(30) **Foreign Application Priority Data**

Sep. 29, 2021 (EM) 008706097-0002

(51) **LOC (14) Cl.** **23-01**

(52) **U.S. Cl.**

USPC **D23/213**

(57) **CLAIM**

The ornamental design for a shower head, as shown and described.

DESCRIPTION

FIG. 1 is a perspective view of a shower head showing our design;

FIG. 2 is a front elevational view;

FIG. 3 is a rear elevational view;

FIG. 4 is a side elevational view;

FIG. 5 is a side elevational view;

FIG. 6 is a top plan view; and,

FIG. 7 is a bottom plan view.

The broken line showing of a shower head is included for the purpose of illustrating portions of the article and forms no part of the claimed design.

1 Claim, 7 Drawing Sheets
